DISPENSER FOR SHAVING CREAM AND TOOTH PASTE OR THE LIKE

Joseph J. Manning, Philadelphia, Pa.

Application August 12, 1948, Serial No. 148,078

Term of patent 7 years

(Cl. D4—3)

To all whom it may concern:

Be it known that I, Joseph J. Manning, a citizen of the United States of America, residing in the city and county of Philadelphia, and State of Pennsylvania, have invented a new, original, and ornamental Design for a Dispenser for Shaving Cream and Tooth Paste or the like, of which the following is a specification, reference being had to the accompanying drawings, forming a part thereof.

Fig. 1 is a front elevation; Fig. 2 is a top plan; Fig. 3 is a left side elevation; Fig. 4 is a right side elevation; and Fig. 5 is a bottom plan view of a dispenser for shaving cream and tooth paste or the like, showing the new design.

I claim:

The ornamental design for a dispenser for shaving cream and tooth paste or the like, as shown.

JOSEPH J. MANNING.
